UNITED STATES PATENT OFFICE.

EMANUEL J. BOYLER, OF NEW HAVEN, CONNECTICUT, ASSIGNOR TO THE GREIST MANUFACTURING COMPANY, A CORPORATION OF CONNECTICUT.

SEWING-MACHINE ATTACHMENT.

1,085,104.

Specification of Letters Patent.

Patented Jan. 27, 1914.

Application filed February 10, 1913. Serial No. 747,388.

To all whom it may concern:

Be it known that I, EMANUEL J. BOYLER, a citizen of Canada, residing at New Haven, in the county of New Haven and State of Connecticut, have invented or discovered certain new and useful Improvements in Sewing-Machine Attachments, of which the following is a specification, reference being had therein to the accompanying drawings.

5 This invention relates to sewing machine attachments, and more particularly to sewing machine hemmers, and has for its object to provide means whereby hemmers or other similar attachments, such as a binder, a 10 braider or corder, or an edge guide, may be mounted on the presser foot in such a manner as to be conveniently removed, when desired, as also in such a manner that it may be adjusted laterally on the presser foot with 15 reference to the position of the needle or direction of movement of the work. To this end the hemmer or other attachment is provided with a shank having a vertical flange or up-turned portion constructed with a 20 double key-hole slot, and in the lower part of the shank of the presser-foot are mounted two headed studs adapted to pass through the larger portions of this key-hole slot, the 25 narrower portions of said slot closely fitting the shanks of the said studs beneath the said heads, when the attachment is mounted on the presser foot. The studs referred to pass loosely through the shank of the presser-foot but with a close fit, and are connected to a 30 spring which is attached to the rear side of the presser-foot by said studs, said spring acting to hold one or both of said studs frictionally against the upturned flange of the attachment so that the attachment will be 35 frictionally retained in place in such a manner that it may be adjusted laterally simply by sliding it slightly one way or the other, and may be readily removed, when desired, by moving the shank to a position which will 40 cause the larger portions of the double key-hole slot to register with the heads of said studs.

45

In the accompanying drawing Figure 1 is a perspective view of the invention in the 50 form of a hemmer attachment. Figs. 2, 3 and 4 are plan, side and rear views, respectively, of the same, and Fig. 5 is a section on line 5—5, Fig. 3.

55 Referring to the drawing, 12 denotes a presser-foot provided with a shank portion

13 by which said foot may be detachably secured to a sewing machine presser-bar in a well-known manner. Mounted on the said presser-foot, in the form of the invention herein illustrated, is a scroll hemmer 14 of 60 well-known construction, said hemmer 14 being provided with a shank 15 having an upturned portion or vertical flange 16 constructed with a double key-hole slot 17. Mounted in the lower part of the shank of 65 the presser-foot are two studs 18 and 19 the heads of which are adapted to pass through the enlarged portions of the double key-hole slot, so that when said enlarged portions are brought into register with said studs the attachment may be applied to the presser-foot, and may then be removed laterally to bring the heads of the said studs into register with the narrower portions of the key-hole slot, 70 so that the attachment will be secured in 75 place on the presser-foot.

The studs 18 and 19 are riveted to a spring 20 mounted at the rear side of the presser foot and held in place by said studs, said spring serving to draw the head of the 80 stud 18 into frictional engagement with the flange 16 of the hemmer shank 15 and thus frictionally hold the hemmer attachment in place, but permitting it to be slid laterally on said studs for the purpose of adjustment, or for the purpose of bringing the enlarged 85 portions of the key-hole slot into register with said studs when the attachment is to be removed. The head of the stud 19 fits closely against the front side of the flange 16 and said head is preferably provided with a slot or nick 21 and a portion of the shank of the presser-foot adjacent said stud is preferably provided with a notch 22. The said stud 19 passes through a washer 23 which is held 90 against the spring 20 by the riveted portion of the said stud, the latter being thus so mounted that it may be turned, if desired.

If it be desired to adjust the hemmer or other attachment laterally on the presser- 100 foot in a more convenient or exact manner than can be done by sliding the same laterally by hand, a screw-driver or similar pointed instrument may be inserted into the slot or nick in the stud 19, with one edge of the 105 screw driver in the said notch 22 in the shank portion of the attachment, so that by turning the screw driver slightly an eccentric adjustment will be afforded by which the attachment may be slid or adjusted lat- 110

erally in an exact or delicate manner, such adjustment being for the purpose of locating the line of stitching at any desired distance from the edge of the hem; and the 5 said attachment will be maintained in any position to which it may be adjusted by reason of the frictional hold of the heads of the studs 18 and 19 on the flange portion 16 of the presser-foot shank.

10 It will be understood that the construction above described affords a convenient means whereby a hemmer may be readily mounted on a presser foot in such a manner as to be conveniently and quickly re- 15 moved if it be desired to replace the same by a hemmer of a different width; and it will also be understood that the hemmer shown in the drawing may be replaced by another attachment of any suitable kind 20 such as a binder, a braider or corder, etc.

The construction above described provides convenient means whereby a hemmer or other attachment may be readily and quickly applied to or removed from its supporting 25 presser-foot or may be adjusted laterally thereon, without requiring the tightening or loosening of a set-screw or similar device, the attachment being retained in any desired position of adjustment on the presser-foot 30 by means of the frictional hold of the heads of the studs against the upturned flange on the shank portion of the attachment.

Having thus described my invention I claim and desire to secure by Letters Patent: 35 1. The combination with a sewing machine presser-foot having a shank portion provided with two headed-studs one of which is loosely mounted for endwise movement in said shank portion, of an attachment, such as a hemmer or the like, having 40 a shank provided with an upturned portion or flange constructed with a double key-hole slot receiving the said studs, the heads of said studs being adapted to frictionally en- 45 gage the said upturned portion or flange

for the purpose of adjustably and removably securing the attachment to the said presser foot, and a spring acting on said loosely mounted stud and serving to hold the head thereof in frictional contact with the 50 shank of the attachment.

2. The combination with a sewing machine presser-foot having a shank portion provided with two headed-studs, of an attachment, such as a hemmer or the like, having 55 a shank provided with an upturned portion or flange constructed with a double key-hole slot receiving the said studs, the heads of said studs being adapted to frictionally engage the said upturned portion or flange 60 for the purpose of adjustably and removably securing the attachment to the said presser foot, and a spring attached to the shank portion of said presser-foot and to which spring the said studs are attached by means 65 of riveted or upset portions of said studs.

3. The combination with a sewing machine presser-foot having a shank portion provided with two headed-studs, of an attachment, such as a hemmer or the like, having 70 a shank provided with an upturned portion or flange constructed with a double key-hole slot receiving the said studs, the heads of said studs being adapted to frictionally engage the said upturned portion 75 or flange for the purpose of adjustably and removably securing the attachment to the said presser foot, one of said studs being provided with a slit or nick and said shank being provided with a notch adjacent to the 80 said stud, to enable the attachment to be adjusted laterally by means of a screw-driver or the like.

In testimony whereof I affix my signature, in presence of two witnesses.

EMANUEL J. BOYLER.
